ELECTRIC CIRCUIT CONTROLLER

Raymond W. Ross, Philadelphia, Pa., and Sigurd H. Seberhagen, deceased, late of Philadelphia, Pa., by Sophie Seberhagen, executrix, Philadelphia, Pa., assignors to Leeds and Northrup Company, Philadelphia, Pa., a corporation of Pennsylvania

Application January 23, 1935, Serial No. 3,194

10 Claims. (Cl. 200—11)

This invention relates to electric circuit controllers and specifically to such controllers known in the art as distributors or selectors. While this invention is of general application, it is particularly suitable for use in connection with multiple-point recording mechanisms such, for example, as those of the type disclosed and claimed in the copending application, Serial No. 75,208, filed April 18, 1936.

10 The circuit controller of this invention comprises a pair of relatively movable contact structures. One of the contact structures includes a pair of spaced contact elements insulated from each other, while the other includes a substantially U-shaped contact element so disposed that relative movement of the contact structures is effective to slide the U-shaped contact element into and out of bridging engagement with the spaced contact elements of the other contact structure. The U-shaped contact element is resiliently supported in its respective contact structure with a limited freedom of motion, in order to equalize the contact pressures at the contact surfaces of the circuit controller.

25 More specifically, in accordance with this invention, the stationary contact structure of the circuit controller comprises a disk of insulation material from which are supported a pair of concentric arcuate contact strips. The second contact structure is pivotally mounted with respect to the first contact structure about the axis of the contact strips and the U-shaped bridging member is supported within a slot in its respective contact structure extending radially 30 of the movable contact structure. The U-shaped contact element is supported within the slot by a loose pivotal mounting on the head of a spherical spring-pressed plunger carried in a recess extending from the bottom of the slot. Thus, 35 the U-shaped contact element may be said to be semi-floating; that is, full-floating except in the direction of its movement, in which it is restricted by the slot in which it is mounted, providing a moderately close fit.

40 For a better understanding of this invention, together with other and further features thereof, reference is had to the following description taken in connection with the accompanying drawing, and its scope will be pointed out in the 45 appended claims.

In the drawing, Fig. 1 is a longitudinal sectional view of a circuit controller embodying the invention;

50 Fig. 2 is a bottom plan view of the circuit controller of Fig. 1 with the enclosing casing removed; and

Fig. 3 is an end view of the movable contact element and its support.

5 Referring now more particularly to the drawing, there is illustrated a circuit controller embodying this invention comprising a supporting frame 10 which may comprise a cup-shaped member having a central opening 10a in which is supported, as by a forced fit, a boss or hub 11. 10 Mounted within the hub 11 is a sleeve 12 depending from the boss 11 and carrying on its lower end a disc or plate 13 of insulating material such as bakelite or other synthetic resin. The plate 13 may be molded directly to the sleeve 15 12 in a well-known manner or, as illustrated, it may be provided with an elongated hub or sleeve 13a locked to the sleeve 12 by means of pin 14. The upper end of the hub 13a of the disc 13 is brought into engagement with the lower shoulder 20 of the boss 11 by means of a lock nut 15 threaded upon the upper portion of the sleeve 12 and engaging the upper face of the boss or hub 11.

25 Supported from the lower face of the disc 13 are stationary contact elements which may preferably be molded directly in the disk 13. The arrangement of the several stationary contact elements may be entirely in accordance with the requirements of the particular application of such a controller. By way of example only, there is 30 shown in Fig. 2 an arrangement of stationary contact elements which has been found particularly suitable for use in connection with an automatic indicating and recording apparatus which forms the subject matter of the aforementioned 35 copending application.

40 Specifically, the stationary contact elements comprise parallel contact strips such as a pair of concentric annular contact rings 16 and 17, the contact ring 17 being divided into a plurality of segments insulated from each other to provide a plurality of individual contact elements. There is also provided an additional pair of concentric annular contact rings 18 and 19, the ring 19 comprising a series of annularly arranged segments 45 as in the case of the ring 17. The ring of contact segments 19 may cooperate both with the ring 18 and with an additional ring 20 disposed within the ring 19. The terminals for connection of the several stationary contact elements to external circuits may be formed directly in the disk 13 during the molding of the contact elements therein or, in certain instances, it may be desirable, in order to reduce the number of external connections, to form certain connections 50 55

Fig. 2 is a bottom plan view of the circuit controller of Fig. 1 with the enclosing casing removed; and

directly at the disk 13, in which case it may be provided with an auxiliary cover plate 21, also of insulation material, the plate 21 preferably fitting closely on the hub 13a to maintain it in proper relationship. The frame 10 has an opening in which is mounted a bushing 22 of insulation material to prevent a chafing of the external conductors to the stationary contact segments, on the edges of the metal supporting frame 10.

10 In the sleeve 12 is journaled a shaft 23 carrying at its lower end the movable contact structure. This structure comprises an elongated bar 24 of insulation material, preferably of synthetic resin, in which is molded a sleeve or hub 25, the member 15 24 and sleeve 25 being secured to the shaft 23 by a set screw 26 threaded in the sleeve 25. In order to aid in properly aligning the movable contact assembly after removal for repair, replacement or cleaning, the upper end of the sleeve 25 is slotted 20 as at 25a, while the shaft 23 is drilled to receive a pin 27. The complementary slot 24a in the member 24 extends only on one side of the shaft 23, thus precluding mounting of the rotating contact assembly on the shaft 23 displaced 180° from 25 its proper position. The insulation member 24 is provided with a longitudinal slot 24b in the bottom of which are drilled or otherwise formed a 30 number of holes 24c in each of which is mounted a spherical headed plunger 28 biased upwardly by a surrounding helical spring 29. The upward movement of the plunger 28 is limited by a split ring 28a fitted on the lower end of the plunger 28.

Supported from the head of each of the plungers 28 is a substantially U-shaped contact bridging element 30 secured thereto by a pin 31. By the term "U-shaped" is meant any analogous shaped functionally similar; that is, one having two arms extending generally in the same direction from a common base member. The hole in 40 the base of the U-shaped contact element is substantially larger than the shank of the pin 31 to provide a limited freedom of movement which, due to the spherical head of the plunger 28, constitutes substantially a universal mounting.

45 However, as shown more clearly in Fig. 3, the width of the bridging element 30 is substantially the same as the width of the slot 24b in which it is mounted, so that the walls thereof, forming abutments, prevent any substantial movement of the element 30 in the direction of motion of the movable contact assembly, which as viewed in Fig. 3 may be to the left or the right, and in Figs. 1 and 2 either clockwise or counter-clockwise.

It will be apparent that the shaft 23 connected 55 to the movable contact assembly may be operated in any desired manner either manually or automatically. By way of example only, there is illustrated a bevel gear 32 secured to the upper end of the shaft 23 as by a set screw 32a, it being understood that the gear 32 may be driven by 60 any suitable mechanism. There is provided also a lower cover member or cup-shaped container 33 having a bayonet slot engaging a pin 34 supported in the frame 10. In certain instances, it 65 may be desirable to fill the cover member 33 with oil or other suitable insulating fluid.

It is believed that the operation of the above 70 described circuit controller will be clear from the foregoing description. In brief, the rotation of the shaft 23 causes the movable contact assembly 24 to rotate about its axis, the several contact bridging elements 30 sliding on their respective contact rings and segments, successively completing the circuits between the contact rings and the several contact segments. The rigid bridging

contact elements 30 may be termed semi-floating; that is, full floating except in the direction of normal movement, so that they readily take up any irregularities or misalignments in the stationary contact elements, securing satisfactory contact engagements under all operating conditions. Also, due to the universal mounting of the contact elements 30 on the spherical heads of the plungers 28, equalized contact pressures at the several contact surfaces are insured. At the same 10 time the circuit controller is extremely simple to manufacture from a practical standpoint.

While there has been described what at present is considered the preferred embodiment of the invention, it will be obvious to those skilled 15 in the art that various changes and modifications may be made without departing from the invention, and therefore the appended claims cover all such changes and modifications as fall within the spirit and scope of the invention. 20

What is claimed:

1. In an electric circuit controller having relatively movable contact structures, one of which has a pair of spaced contact elements insulated from each other, and the other of which has a recess opposed to said pair of contact elements, the combination of a spherical headed plunger reciprocably mounted in said recess and having a pin secured in its head, a substantially U-shaped contact element loosely pivoted on said pin, said contact element being so disposed that relative movement of said contact structures effects a bridging engagement and disengagement of said pair of contact elements by said U-shaped contact element, and a helical spring surrounding 30 said plunger for biasing it toward said pair of contact elements.

2. In an electric circuit controller having relatively movable contact structures, one of which has a pair of spaced contact elements insulated from each other, and the other of which has a slot extending transversely to the direction of relative movement, the combination of a spherical headed plunger carried by said second contact structure with its head projecting into said slot, 40 a substantially U-shaped contact element supported from the head of said plunger with a limited freedom of motion and bearing thereon, said contact element being so disposed that relative movement of said contact structures effects a 45 bridging engagement and disengagement of said pair of contact elements by said U-shaped contact element, and resilient means for biasing said contact elements into engagement.

3. In an electric circuit controller comprising 55 a stationary contact structure including a pair of concentric arcuate contact strips insulated from each other, a second contact structure pivotally mounted with respect to said stationary contact structure about the axis of said contact strips, a substantially U-shaped contact element, the combination of means for universally and resiliently supporting said contact element from said pivotally mounted contact structure for bridging engagement and disengagement of said 60 contact strips upon pivotal movement thereof, said supporting means having a slot whose wall portions substantially restrict universal movement of said contact element tangential to its 65 pivotal movement.

4. In a circuit controller having a pair of spaced contact members, supporting structure therefor, the combination of contact structure comprising a second supporting structure relatively movable in a plane substantially parallel 70 75

to the faces of said contact members and having abutments extending normal to the direction of relative movement of said supporting structures, a U-shaped contact element so disposed between said abutments that each of its legs respectively is adapted to engage one of said contact members, and means for pivotally connecting said contact element to said second supporting member for substantial movement about an axis parallel to said direction of movement, said abutments restricting movement of said element about an axis normal to said direction of movement.

5. In a circuit controller having a pair of concentric annular contact rings at least one of which is divided into a plurality of segments, supporting structure for said rings, the combination of contact structure comprising a second supporting structure, said structures being relatively pivoted about the axis of said rings, abutments carried by said second supporting structure and extending substantially radially of said pivotal axis, a U-shaped contact element so disposed between said abutments that its legs engage said contact rings respectively, and means for pivotally connecting said contact element to said second supporting structure for substantial movement between said abutments about an axis substantially normal to said first-named pivotal axis and to the radius therefrom to said second named pivotal axis, said abutments restricting movement of said element about an axis parallel to said radius.

6. In a circuit controller having a pair of spaced contact members, supporting structure therefor, the combination of contact structure comprising a second supporting member relatively movable in a plane substantially parallel to the faces of said contact members, a slidible plunger carried by said second supporting member for movement normal to said plane, resilient means for biasing said plunger toward said contact members, a U-shaped contact element carried by said plunger for pivotal movement about an axis parallel to the relative movement of said structures, the legs of said element respectively engaging said spaced contact members, and structure for restricting movement of said element about an axis normal to the relative movement of said structures.

7. A circuit controller unit comprising a supporting sleeve, annular contact rings concentric with and carried by said sleeve, a rotatable shaft extending through said sleeve, a rigid radial arm supported by said shaft and provided with a radial slot the open end of which is presented to said contact rings, a U-shaped contact element whose legs closely fit between the radial sides of said slot, an elongated plunger carried by said arm and having a spherical end terminating in said slot to provide a universal mounting for said

contact element, a pin loosely supporting said contact element against said spherical end, and resilient means acting upon said plunger to press its spherical end against said contact element to produce substantial contact pressure between the respective legs of said contact element and said contact rings.

8. A circuit controller unit comprising supporting structure, a rotatable shaft extending through and supported by said structure, at least three contact rings concentric to said shaft carried by said supporting structure, a rigid, radial arm rotatable with said shaft having a radial slot presented to said contact rings, at least two U-shaped contact elements radially disposed in said slot and closely fitting the substantially radial sides thereof, the legs of each of said elements engaging different contact rings, plungers carried by said arm for independent rectilinear movement normal to the plane of said contact rings and terminating in said groove to provide universal mountings individual to said contact elements, and resilient means for biasing said plungers toward said plane.

9. A unitary contact assembly comprising a supporting member having an opening, an elongated plunger slidable within said opening and having a spherical end, a spring within said opening one end of which bears against said supporting member and the other end of which bears against said plunger, a contact element having two arms extending in the same direction from a base member, a pin loosely supporting said base member centrally of said spherical end of said plunger, and means associated with the opposite end of said plunger for limiting the outward movement of said plunger to retain said spring under compression.

10. A unitary contact assembly comprising a supporting member having an opening, an elongated plunger disposed within said opening and having a rounded end extending outwardly from one side of said member, a spring within said opening for biasing said plunger for movement toward said one side of said member, and a U-shaped contact element having legs extending outwardly from said plunger, the portion interconnecting said legs having an opening therethrough, and a pin extending through said opening and loosely retaining said element against said rounded end of said plunger for universal movement of said element, said supporting member having a recess the walls of which substantially restrict universal movement of said element only in one direction.

RAYMOND W. ROSS.

SOPHIE SEBERHAGEN,
